UNITED STATES PATENT OFFICE.

HERBERT J. FRINK, OF HOLYOKE, MASSACHUSETTS.

PULP-GRINDING MACHINE.

SPECIFICATION forming part of Letters Patent No. 636,225, dated October 31, 1899.

Application filed July 5, 1899. Serial No. 722,798. (No model.)

To all whom it may concern:

Be it known that I, HERBERT J. FRINK, of Holyoke, county of Hampden, State of Massachusetts, have invented an Improvement in Pulp-Grinding Machines, of which the following description, in connection with the accompanying drawings, is a specification, like letters on the drawings representing like parts.

10 This invention relates especially to apparatus for grinding wood-pulp and the like; and it has for its object more particularly the production of novel means for guiding or directing the piston-rods which operate the 15 pressure devices employed to force the material to be ground against the grinder.

Wood-pulp grinders usually comprise a curb or case covering the grinding-stone above suitable bed-plates, and the wood-boxes 20 are firmly secured to the case. A hydraulic cylinder is bolted to each wood-box and is usually made of cast-iron lined with brass or bronze, a suitable piston having an attached piston-rod provided at its inner end with a 25 follower or presser, which acts upon and forces the wood in the wood-box against the grinder. It is the usual practice to extend the piston-rod through suitable stuffing-boxes, one at each end of the cylinder, a gland of 30 brass or bronze being fastened in the stuffing-box by tap-bolts or otherwise, and in practice such construction has been found very objectionable owing to the friction on the piston-rod caused by the unequal bearings there- 35 for provided by the two stuffing-boxes.

The men employed to tend wood-pulp grinders are not skilled mechanics, and when a stuffing-box leaks the attendant is very apt to tighten it up until the leakage is overcome, 40 without paying much heed to the alinement or proper setting of the bearing, and as a consequence a large proportion of the power applied in the cylinder is lost in friction and the output of the grinder correspondingly less- 45 ened.

If the upper extension of the piston-rod is not used, it is practically impossible to guide the follower with accuracy and there is more or less side movement of the follower, due to 50 the variation in the sizes of the sticks of wood, and the piston and cylinder are worn unequally.

By my invention I provide an upper bearing or guide for the piston-rod extension, which maintains the latter in proper alinement, while obviating the tight fit and consequent friction resulting from the use of a stuffing-box at each end of the cylinder.

Figure 1 in side elevation represents a sufficient portion of a grinding-machine to be understood, with one embodiment of my invention applied thereto, the valve-chests and connections being omitted from the drawings for the sake of clearness. Fig. 2 is an enlarged diametral sectional view of one of the pressure-cylinders, taken at the upper end thereof to more clearly illustrate my invention. Fig. 3 is an end view of the guide or bearing forming a part of my invention, and Fig. 4 is a side elevation thereof.

Referring to Fig. 1, the grinding-stone G, curb or casing C, covering the grinder above the bed-plate B, the open-ended wood-boxes A, mounted on the curb, and the cylinders D, secured to the tops of the wood-boxes in any 75 suitable manner, may be and are of usual construction well known in this type of apparatus. The piston P in each cylinder and of usual construction has rigidly secured to it a piston-rod P', extended through a stuffing- 80 box b (see dotted lines, Fig. 1) at the inner end of the cylinder, and a follower P^x is mounted on the end of the rod extended into the wood-box A to force the wood against the grinder. The upper cylinder-head D' (see 85 Fig. 2) is provided with a central hub or boss D², through which is loosely extended the piston-rod extension P², there being an ample clearance d^x between the opening in the inner end of the hub and the piston-rod extension. A guide and bearing for said extension is placed in the hub D², said guide being shown separately in Figs. 3 and 4 as a bushing f, longitudinally ribbed exteriorly at f', the ribs extending beyond one end of the 95 body portion f, and I prefer to make the guide of composition metal or bronze. The ribs f' snugly enter the hub D² and hold the guide from lateral movement, the latter being maintained firmly in place by an elongated hood, 100 shown as tubular and threaded into the hub at h^x to bear against the outer end of the guide, the hood receiving the piston-rod extension P² on its outer stroke and being shown

as closed fluid-tight by a screw-cap H'. The bushing f thus acts as a bearing and guide for the piston-rod extension and fits only snugly enough for that purpose, the spaces 5 between the ribs f' forming channels f'', Fig. 3, which permit the free passage of the fluid contents of the cylinder into and out of the hood as the piston is moved in the cylinder. I am thus enabled to avoid all of the friction 10 which would be caused by using the customary form of stuffing-box, while accurately guiding and maintaining the piston-rod and its extension in perfect alinement and properly holding the follower to its work.

15 Having described my invention, what I claim as new, and desire to secure by Letters Patent, is—

1. In a pulp-grinder, a pressure-cylinder, its piston, a piston-rod having an extension 20 loosely passed through the outer cylinder-head, a channeled guide-bearing mounted on the latter, for the rod extension, and a hood

secured to the cylinder-head and maintaining the guide-bearing in place, the hood communicating with the cylinder through the channels of the guide and inclosing the exposed portion of the rod extension. 25

2. In a pulp-grinder, a pressure-cylinder having its outer head provided with a hollow boss, a guide therein and provided with fluid-passages, a closed hood mounted on the head and retaining the guide in place, a piston, and an extension-rod attached thereto, extended loosely through the boss and into the hood, the guide forming a bearing for and directing 30 35 said extension-rod.

In testimony whereof I have signed my name to this specification in the presence of two subscribing witnesses.

HERBERT J. FRINK.
